DESIGN FOR A LIGHTING FIXTURE

Edwin F. Guth, Webster Groves, Mo.

Application December 5, 1934, Serial No. 54,280

Term of patent 3½ years

To all whom it may concern:

Be it known that I, Edwin F. Guth, a citizen of the United States, residing at Webster Groves, in the county of St. Louis, and State of Missouri, have invented a new, original, and ornamental Design for a Lighting Fixture, of which the following is a specification, reference being had to the accompanying drawing, forming part thereof, in which—

The figure is a perspective view of a lighting fixture embodying my improved design.

I claim:

The ornamental design for a lighting fixture as shown.

EDWIN F. GUTH.
